CLAIM

The ornamental design for a fruit holder, as shown and described.

DESCRIPTION

The invention is a device for holding various fruits and hanging bananas and grapes.

FIG. 1 is a front perspective view of the fruit holder showing my new design;

FIG. 2 is a front elevation view thereof and it is identical to the rear elevation view;

FIG. 3 is a right side elevation view thereof and it is identical to the left side elevation view;

FIG. 4 is a top plan view thereof; and,

FIG. 5 is a bottom plan view thereof;
